UNITED STATES PATENT OFFICE.

OTHNIEL H. TALBOTT, OF ELDORADO SPRINGS, MISSOURI.

PHOTOGRAPHIC-PLATE HOLDER.

No. 922,356.

Specification of Letters Patent.

Patented May 18, 1909.

Application filed June 5, 1908. Serial No. 436,911.

To all whom it may concern:

Be it known that I, OTHNIEL H. TALBOTT, a citizen of the United States of America, residing at Eldorado Springs, in the county of 5 Cedar and State of Missouri, have invented new and useful Improvements in Photographic-Plate Holders, of which the following is a specification.

My invention relates to improvements in 10 photographic plate holders, and its primary object is the provision of a device of this character with means by which the plate may be readily and quickly centered within the holder, said means being preferably au- 15 tomatic in its operation.

A further object of my invention is the provision of a plate holder with means by which the position of the plate within the holder can be readily and quickly changed 20 without opening the holder.

A still further object of my invention is the provision of a plate holder which is simple, durable and efficient, and which may be manufactured and sold at a comparatively 25 low cost.

With the above and other objects in view, the invention consists in the construction, combination and arrangement of parts hereinafter fully described, claimed and illus- 30 trated in the accompanying drawing, wherein:

Figure 1 is a sectional view taken on a plane extending centrally and vertically through a photographic plate constructed in 35 accordance with my invention. Fig. 2 is a sectional view taken on the vertical plane indicated by the line 2—2 of Fig. 1. Fig. 3 is a sectional view taken on a plane extending centrally and horizontally through the plate 40 holder, and Fig. 4 is a perspective view illustrating the means by which the plate carrier can be operated to reverse the position of the plate within the holder, and the means by which the plate carrier is held against acci- 45 dental displacement.

Referring to the drawing by reference numerals, 1 designates the sides, 2 the top, 3 the bottom and 4 the back of a plate holder of the usual or any appropriate construction.

50 My invention consists in the provision of a plate carrier adapted to automatically center the plate within the holder and adapted to be

operated to reverse the position of the plate within the holder. The plate carrier comprises a body 5 which preferably consists of a 55 rectangular piece of metal, wood or any other material suitable for the purpose. The body 5 is provided with elongate slots 6 which open out through the end edges thereof, and which are disposed in a plane which extends 60 centrally and longitudinally through the body. Clamp carrying members 7 and 8 are secured to the body 5 for relative movements longitudinally thereof through the medium of lugs 9 which are disposed in the slots 6. 65 The clamp carrying members are held against accidental displacement through the medium of plates 10 which are secured to the lugs 9 and which engage the body 5 on opposite sides of the slots 6. 70

The relative movements of the clamp carrying members 7 and 8 are synchronized through the medium of a lever 11 and links 12. The lever 11 is pivotally mounted at a point intermediate its ends upon the body 5 75 and the links 12 are pivotally connected to the lever and to the clamp carrying members. The clamp carrying members are resiliently held in their innermost positions by means of a contractile spring 13 which is se- 80 cured at its ends to said members. The member 8 has secured thereto a single clamp 14 which is provided with a groove 15 extending longitudinally of the body 5. The clamp of the carrying member 7 consists of 85 a pair of relatively movable jaws 16, each of which includes a flange 17 and a groove 18. The relative movements of the jaws 16 are held in a plane extending transversely of the body 5, that is, in a plane extending at right 90 angles to the plane of the movements of the clamp carrying members 7 and 8. The jaws 16 are movably mounted upon the member 7 through the medium of lugs, not shown, which are formed thereon for engagement in 95 grooves 19 which extend longitudinally of the member 7 and which open out through the ends thereof.

The members of the clamps 1 are synchronized through the medium of a lever 20 100 and links 21. The lever 20 is pivoted at a point intermediate its ends upon the member 7 and the links 21 are pivotally connected to the lever and to the jaws. The jaws 16 are

resiliently held in their innermost positions by means of a contractile spring 22 which is secured at its ends to the jaws.

In practice, one corner of the plate is inserted in one of the jaws 16 of the clamp carried by the member 7, after which the opposite corner of the plate is inserted in the other jaw of the clamp. After the plate has been inserted in the jaws of the clamp, it is inserted in the clamp 14 which is carried by the member 8, it being understood that the end edges of the plate are disposed in the grooves 15 and 18 of the clamps, and that the flanges 17 of the jaws 16 engage the side edges of the plate.

As the spring 22 tends to hold the jaws 16 in their innermost positions, in which positions they are equally spaced from the longitudinal center of the body 5, and as the spring 13 tends to hold the members 7 and 8 in their innermost positions, in which positions they are equally spaced from the transverse center of the body 5, it should be apparent that said springs will automatically center the plate in the frame. The plate is held against movement in the clamps by means of a spring member 23 which is secured to the body 5 for engagement with the rear surface of the plate, said member being secured at one of its ends to the body.

In order to permit the position of the plate within the holder to be reversed, the plate carrier is rotatably mounted upon the back 4 of the plate holder through the medium of a stud 24. An operating head 25 is secured to the stud 24, and a spring catch 26 is secured to the stud 24 for engagement in one of two notches 27 to secure the plate carrier in its adjusted position. A stop 28 is secured to the inner surface of the back 4 of the plate holder to limit the movement of the plate carrier in both directions.

From the foregoing description taken in connection with the accompanying drawing, the construction and mode of operation of the invention should be understood without a further extended description.

Changes in the form, proportions and minor details of construction may be made within the scope of the claims without departing from the spirit or sacrificing any of the advantages of the invention.

Having fully described and illustrated my invention, what I claim is:

1. The combination with a photographic plate holder, of movable clamps, a spring connected to the clamps and adapted to normally retain them in their innermost positions, a synchronizing connection between the clamps, one of said clamps consisting of jaws mounted for movements in a direction at right angles with relation to the direction of movement of the clamps, a spring connected to the jaws and adapted to retain

them in their innermost positions, and a synchronizing connection between the jaws. 65

2. A photographic plate holder including a pair of movably mounted clamps, a spring connecting the clamps, one of said clamps consisting of jaws mounted for movement in a direction at right angles to the direction of movement of the clamps, and a spring connecting the jaws. 70

3. A photographic plate holder, including a rotatably mounted body, members movably mounted upon the body, a clamp secured to one of the members, and jaws movably mounted upon the other member. 75

4. A photographic plate holder including a pair of movably mounted members, a synchronizing connection between the members, a clamp secured to one of the members, jaws movably mounted upon the other member, and a synchronizing connection between the jaws. 80

5. A photographic plate holder including a rotatably mounted body, a pair of members movably mounted upon the body, a spring connecting the members, a synchronizing connection between the members, a clamp secured to one of the members, jaws movably mounted upon the other member, a spring connecting the jaws, and a synchronizing connection between the jaws. 85

6. The combination with a photographic plate, of a holder therefor, said holder consisting of movably mounted clamps one of which is adapted to engage one edge of the plate, the other of said clamps consisting of jaws mounted for movement in a direction at right angles with relation to the direction of movement of the clamps and adapted to engage the other edges of the plate. 95

7. The combination with a photographic plate, of a holder therefor, said holder including a pair of movably mounted members, a clamp secured to one of the members and adapted to engage one edge of the plate, and jaws movably mounted upon the other members and adapted to engage the other edges 100 of the plate. 105

8. A photographic plate holder including a back provided with a plurality of notches, a body rotatably mounted upon the back, a spring catch carried by the body for engagement in one of the notches, members movably mounted upon the body, a clamp secured to one of the members, and jaws movably mounted upon the other member. 115

9. The combination with a photographic plate, of a holder therefor, said holder including a movably mounted plate, a clamp adapted to hold the plate against accidental movement in one direction, and movably mounted jaws adapted to hold the plate against accidental movement in any other direction. 120

10. The combination with a photographic plate, of a holder therefor, said holder includ-

ing a pair of movably mounted members, a clamp secured to one of the members and adapted to hold the plate against movement in one direction, and jaws movably mounted upon the other member and adapted to hold the plate against movement in any other direction.

In testimony whereof I affix my signature in presence of two witnesses.
